JOHN H. LIVINGSTON, OF PROVIDENCE, RHODE ISLAND.

Letters Patent No. 88,050, dated March 23, 1869.

IMPROVEMENT IN BOOTS.

The Schedule referred to in these Letters Patent and making part of the same.

To all whom it may concern:

Be it known that I, JOHN H. LIVINGSTON, of the city and county of Providence, in the State of Rhode Island, have invented a new and useful Improvement in Boots; and I do hereby declare that the following specification, taken in connection with the drawings making a part of the same, is a full, clear, and exact description thereof.

Figure 1 is a front view of the leg of a boot, and

Figure 2, of the "upper," or vamp, both as they appear when cut out, before being stitched together and crimped.

Figure 3 is a view of the back side of the same parts stitched together, partially lined with cloth, and ready for crimping.

Figure 4 is a view of the same parts crimped.

My improvement consists in so constructing a boot that the "upper," or vamp, and the "counter," shall be made of one entire piece, whereby I am enabled to avoid the presence of side seams, or those seams which have heretofore been required to enable the counter to be united to the vamp.

The advantages which result from my improvement are—

First, the avoidance of seams at which the boot most frequently rips, and which it is impossible to join securely after becoming ripped, without making an ugly outside seam;

Second, in avoiding the presence of any seam, to chafe the foot at these points; and

Third, in obtaining, by the greater facility with which the boot can be put upon the last, a more perfect fit.

In the drawings—

A is the boot-leg.

The vamp is shown at B, and is intended to be stitched to the leg, as shown at fig. 4, which is now

the usual way in making fine boots, the leg-portion being frequently of morocco leather, while the vamp is of calf-skin.

The portions B¹ B² of the vamp constitute the counter, and are a part of the vamp, the vamp being cut of such a pattern that the portions will be able to be brought around the heel of the last to form the counter. The single seam, joining them together, is on the back side.

The leg and vamp having been united, lined, and crimped, (a suitable crimping-block, specially adapted to this improvement, being employed,) the leg is sewn up in the usual way, and then turned right-side out.

The counter having been duly stiffened, as is usual, the seam is whipped together and covered with an ornamental patch, stitched to the counter around its edge, of the form shown at Figure 6.

The boot is now ready to be put upon the last, and when soled, is treed and finished in the usual way.

Boots having legs, uppers, and counters, made from a single piece of material, have been manufactured and sold to a limited extent only, owing to the impracticability of thus producing a well-bent, neatly-fitting ankle. To obviate this objection so long existing, I seek to, and do, practically, accomplish by my invention.

What I claim as my invention, and desire to secure by Letters Patent, is—

The improvement in the manufacture of boots, which consists in making, independent of the leg, the counter and vamp of one piece of material, when constructed as herein described, for the purpose specified.

JOHN H. LIVINGSTON.
